CATHODE RAY TUBE DETECTOR CIRCUITS

Clarence W. Hansell, Port Jefferson, Long Island,
N. Y., assignor to Radio Corporation of
America, a corporation of Delaware

Application January 14, 1930. Serial No. 420,657

13 Claims. (Cl. 250—27)

My present invention relates to detectors, and more particularly to detector circuits embodying a space discharge device of the cathode ray type, the detector circuit being such that the output is 5 much less affected by undesired emission variations than the circuits now in common use.

In my copending application Serial Number 418,281 filed January 3, 1930, there has been disclosed a method of, and means for, eliminating 10 tube noises in the final output of high frequency energy amplifiers, it being there explained that such tube noises occur because of actual irregularities in the rate of emission of electrons from the tube cathode, the method disclosed permitting 15 greater radio frequency amplification to be used so that smaller values of radio frequency energy can be amplified successfully. Briefly, the said copending application discloses an amplifier circuit which comprises an electron dis- 20 charge device of the cathode ray type including a cathode, a plurality of anodes electrostatically shielded from the cathode, the anodes being connected in such a manner that variations in emission from the cathode result in equal and oppo- 25 site variations in the anode output circuit whereby the disturbing anode currents balance out and no noise is present in the output of the amplifier.

Now, I have found that the novel cathode ray tube lends itself satisfactorily to operation in 30 circuits for detecting amplitude modulation of a carrier wave, by greatly reducing the background of noise, and consequently increasing the range of useful signal reception.

Accordingly, it is one of the main objects of 35 my present invention to provide a method of, and means for, reducing tube noises in the final output of a high frequency energy detector, the said means including a cathode ray tube embodying an anode circuit arranged in such a manner 40 that any variations in emission from the tube cathode or any variations in anode and control electrode power supply potentials will result in opposite variations in the said anode circuit, with the result that less tube noise will be impressed 45 upon the input of subsequent stages of audio amplification.

Another important object of the present invention is to provide a circuit for detecting amplitude 50 modulation of a carrier wave of high frequency, which circuit includes a cathode ray tube, comprising an electron emission source, and a plurality of anodes electrostatically shielded from the said source, the anodes being connected in such a manner that variations in emission from 55 the said source will result in opposite variations

in the anode output circuit whereby the currents which result from the emission variations will balance out and less noise be present in the audio output of the detector circuit.

Still another object of the invention is to provide 60 a cathode ray tube capable of sensitive detection of amplitude modulated carrier waves when arranged in a detector circuit connected for eliminating noises due to variations in cathode emission, which tube includes a cathode, a pair 65 of anodes electrostatically shielded from the cathode, all points on the cathode being substantially equi-distant from the two anodes, and one or more control electrodes symmetrically disposed with respect to the anodes and cathode 70 and causing deflections in the electron stream, the input circuit of the tube being so arranged that amplitude modulated carrier waves impressed thereon are readily rectified.

Other objects of the invention are to improve 75 generally the efficiency of detector circuits embodying electron discharge devices, and to, further, provide an electron discharge tube acting as a detector which is durable and reliable in operation, possesses a high useful detection range, a 80 minimum of the action from the output circuit back to the input circuit, and may be readily arranged in a detector circuit to reduce tube noises arising from irregularities in cathode emission.

The novel features which I believe to be characteristic of my invention are set forth in particularity in the appended claims, the invention itself, however, as to both its organization and method of operation will best be understood by 90 reference to the following description taken in connection with the drawing in which I have indicated diagrammatically several circuit organizations whereby my invention may be carried into effect.

In the drawing,

Fig. 1 diagrammatically shows a detector circuit embodying the invention,

Fig. 2 is a diagrammatic representation of a modified form of detector circuit.

Referring to the accompanying drawing, in which like characters of reference indicate the same parts in the different figures, there is shown in Fig. 1 a cathode ray tube detector circuit for detecting amplitude modulation of a carrier 105 wave, having its tuned input circuit 1, 2 coupled, as at M', to a source of amplitude modulated radio frequency energy, the latter being generally designated as "modulated radio input". The output circuit of the tube includes the primary 3 of an 110

audio transformer A having a pair of series connected capacities 4, 4' connected in shunt therewith, the connection between the capacities being tapped, as at point 5, and grounded for short circuiting radio frequency components of current in the anode circuits.

The secondary 6 of the audio transformer A may be connected to any utilization circuit, generally designated as "audio output" which circuit may be one or more stages of audio amplification, 10 head phones, loud speaker or a recorder.

I will not, in this application, describe the construction of the cathode ray tube in great detail for the reason that the tube has been so described 15 in the aforementioned copending application, but will briefly explain sufficient of the structure to enable the present detector circuit to be more fully understood. The tube consists of three insulating sections 5', 6' and 7. Section 5' has 20 sealed in it the cathode or filament 8, the latter being heated by a source of current A'.

A pair of anodes 9, 9' are disposed adjacent an opening in insulating section 7, the said opening being closed by a screen grid or electrostatic 25 shielding member 10. The shield 10 is retained in parallelism with the anodes 9, 9' by a metal cylinder 11, the latter having its opposite ends sealed to insulating sections 6' and 7. A second metal cylinder 12, has its opposite ends sealed to insulating sections 5' and 6'. A pair of wires 13, 30 13' having the greater portion of their length substantially parallel, are sealed to the section 5 at an end thereof.

In order to mount the tube an annular, metallic, 35 mounting and shielding member 14 is provided, the latter member contacting with the exterior of the metal cylinder 11, the member 14 being shown for the sake of simplicity as a single line, it being understood that this structure is 40 described in detail in my aforementioned copending application. This shielding member 14, when the tube is in operation, serves to cover the opening between two shielded compartments containing the input and output circuits so that there is 45 no reaction from the output circuit back into the input circuit due to electrostatic or electromagnetic coupling.

The two anodes 9 and 9' are electrostatically 50 shielded from all other parts within the tube by the shield grid 10. The two control electrodes 13, 13' are symmetrically spaced with respect to the anodes and filament 8, it being understood that only one control electrode can be employed, if desired. The filament 8, furthermore, is designed with a relatively large surface area; a low 55 heating temperature is preferably used to minimize, at the beginning, the amount of emission variation, the effects of which it is desired to reduce or eliminate. Again, all points on the filament 8 should be as nearly as possible equidistant from the two anodes 9 and 9' so that emission variations, which occur in spots or unequally 60 over the cathode area, are more nearly balanced in their effect on the two anodes.

I will now describe the connections between 65 the tube, the tuned input circuit, and the output circuit which will reduce noise resulting from variations in cathode emission, and which will permit more variations in plate and grid power supply voltages. Positive potential is applied to the screen grid 10 and the anodes 9 and 9' for the 70 tube from current sources D and B respectively. The positive terminal of the source B is connected by a lead 15 to the midpoint of inductance coil 3.

75 A lead 16 connects the positive terminal of

source D to the shielding member 14. The filament heating source A' has shunted across it a by-pass condenser 20, the positive terminal of the source and one lead of the filament being grounded, it being also observed that one terminal of the condenser 20 is also grounded.

One of the control electrodes 13' is connected to the high potential side of the tuned input circuit 1, 2 and is negatively biased from a source C through a lead 25. The other control electrode 13 is connected to the positive terminal of the source C by a lead 26, it being observed that the electrode 13 is connected to the cathode lead of the filament through a capacity 21. The metallic cylinder 12 has negative potential applied to it, for concentrating the electronic stream issuing from the filament 8, by means of a lead 19 connected between the negative terminal of source E and the cylinder. The low potential side of the variable condenser 2 in the input circuit of the tube is grounded through a capacity 22.

I have represented the electronic stream issuing from the cathode or filament 8 by means of a series of dotted lines 30 passing between the control electrodes 13 and 13'. The middle of these 100 lines shows the mean position which the stream is made to take when the input circuit has energy from the transmitter carrier wave impressed on it, but this carrier is not being modulated. As soon as the incoming carrier is modulated the mean 105 position of the stream is varied in accordance with the modulation, and a differential variation is set up in the currents to the anodes 9 and 9' resulting in a current corresponding to the modulation in the output circuit 6.

The reason for the variation in the mean position of the electron stream, which results in the useful output, is that the pull on the electrons in the stream varies not only with the potential of the electrodes 13 and 13' but also with the spacing of the electrons from the electrodes. Thus, when electrode 13' has a positive radio frequency potential, it attracts the electron stream (or repels it less), and the displacement of the stream is toward that electrode.

The displacement causes the pull on the stream to increase and this, in turn, increases the displacement. When the electrode 13' has a negative radio frequency potential, it repels the stream (or attracts it less), and the stream is displaced 125 away from the electrode.

In this case, however, the displacement reduces the force and the total deflection is therefore less than would be caused by an equal positive swing on electrode 13'. It is also to be noted that 130 an increase in radio frequency potential on the control electrode increases the deflection of the stream toward the electrode more rapidly than it increases the deflection away from the electrode. A decrease in radio frequency potential decreases 135 the deflection toward the electrode faster than it decreases the deflection away from it. The result is a variation in the mean position of the electron stream in accordance with the modulation, and this causes the differential variation in the currents to the two anodes 9 and 9' producing a useful output from the tube which is substantially a copy of the modulation which is to be detected. This form of detection corresponds closely to the detection which may be obtained from the ordinary type of vacuum tube due to its asymmetrical grid voltage-plate current characteristic.

In Fig. 2, I have shown a modified form of detector circuit employing a cathode ray tube in which the circuit elements similar to those in 150

Fig. 1 are designated by the same reference numerals. In this circuit, it will be noted that the input and output circuit are the same as in Fig. 1, with the exception that a leak resistance R is connected between the tuned input circuit 1, 2 and the negative terminal of battery C through lead 25.

Again, the metal cylinder 12 is negatively biased from a source 31 which is connected through a lead 19 to the negative terminal of the battery B . The control electrode 13, instead of being connected to the positive terminal of battery C , as in Fig. 1, is connected to lead 19, thus being positively biased by the source 31 with respect to cylinder 12, but negative with respect to electrode 13 and cathode 8. However, it is to be noted that the values and polarities of the potentials applied to the electrodes by the sources B , C , D , E and 31 may be varied according to the design of the tube and conditions under which it is operated.

It will be further noted that the filament circuit includes a battery source A' which has connected in shunt therewith a pair of series connected radio frequency bypass condensers 40', the connection between which condensers is grounded. The midpoint of source A' is connected by a lead 41 to the positive terminal of source C .

This modified form of detector circuit depends for its action upon the rectification of radio frequency energy through electrode 13' which causes a unidirectional component of current to flow through the resistance R the value of which varies with the amplitude or modulation of the carrier wave which is to be received. This variable unidirectional current causes the average potential of electrode 13' to vary in accordance with the modulation, and this variation in potential causes a deflection in the mean position of the electron stream so as to differentially vary the currents to anodes 9 and 9'. This gives an output from the tube which is substantially a copy of the modulation which is to be detected. The action of the resistance R in this case is quite similar to that of the grid leak in the common type of detector.

It will thus be seen that I have discovered a new method, and devised novel means for reducing tube noises in the output circuits of detectors, which noises arise because of cathode emission variation, or variations in power supply voltages, the method essentially consisting in balancing out anode currents arising because of the said emission variations and simultaneously differentially varying the path of an electron stream between the cathode and anode by radio frequency currents to be detected in order to produce useful variation in anode output. It is to be understood, of course, that the proportions of the tube may be made different from those shown in the figures, and furthermore that the cylindrical electrodes need not be employed as the outside envelope of the tube.

Again, the tube may be arranged for regeneration from the output circuit back to the input circuit to increase its sensitivity as a detector. Thus, the employment of this new type of cathode ray tube as a detector when employed with regeneration would make possible the successful development of the super-regenerative type of receiver. The tube should be relatively free from hum when alternating current is used on the filament, so that it can fit in well with recent developments of alternating current operated receivers.

While I have indicated and described several systems for carrying my invention into effect, it will be apparent to one skilled in the art that my invention is by no means limited to the particularly organizations shown and described, but that many modifications in the circuit arrangements, as well as in the apparatus employed may be made without departing from the scope of my invention as set forth in the appended claims. In particular, I wish to point out that the detailed proportions and constructions of the cathode ray tube and associated circuits shown will undoubtedly be modified by careful considerations of detailed design and to permit of constructing the tube with less practical difficulties.

What I claim is:

1. A method of detecting modulated radio frequency currents which comprises emitting a stream of electrons towards a pair of electrically balanced anodes, combining a stream at a mean position between a pair of differentially biased control electrodes, impressing modulated radio frequency energy upon the control electrodes, and electrostatically shielding said anodes from said control electrodes.

2. A method of detecting radio frequency currents which comprises projecting a stream of electrons from a cathode towards a pair of symmetrically connected anodes, maintaining the flow of the stream at a mean position adjacent one or more control electrodes, impressing modulated alternating current energy across an impedance connected between the cathode and control electrodes whereby one of said control electrodes is variably biased in accordance with said modulation, and utilizing said variable bias to deflect the stream from said mean position whereby the currents to said anodes are differentially varied in correspondence to said modulation.

3. The method of detecting modulated high frequency currents which comprises projecting a stream of electrons between a pair of control electrodes, disposing a pair of symmetrically connected anodes in the path of said stream, differentially biasing said control electrodes to maintain the stream at a mean position between said electrodes, and impressing modulated high frequency currents upon said electrodes to produce deflections of said stream from said mean position corresponding to the modulation whereby currents in said anodes are varied in accordance with said modulation.

4. Means for demodulating electrical oscillations including a cathode ray electron discharge device having a plurality of anodes, a plurality of control electrodes and a cathode, a symmetrical circuit connecting said anodes to said cathode, means for tuning said circuit, an input circuit connected between one of said control electrodes and said cathode, means for tuning said circuit, and means for maintaining each of said control electrodes at a different direct current potential with respect to said cathode.

5. Means for demodulating signal modulated currents including a cathode ray electron discharge device having a plurality of anodes, a plurality of control electrodes, an emission element substantially equidistant from each of said anodes, and a screening electrode interposed between said anodes and said cathode, a symmetrical circuit connecting said anodes to said cathodes, means for tuning said circuit, means for applying direct current potential to said anodes, means for applying a different direct current

- potential to said screening electrode, an input circuit connecting one of said control electrodes to said cathode, and means for applying different direct current potentials to each of said control electrodes. 80
6. A demodulation device including an emission element, a plurality of anodes equally spaced from said emission element, control electrodes, a screen grid electrode interposed between said anodes and said cathode, an output circuit connected between said anodes, an input circuit connected between said cathode and one of said control electrodes, and means for applying equal direct current biasing potentials to each of said anodes and different direct current biasing potentials to each of the other electrodes. 85
7. Means for rectifying electrical oscillations including a cathode ray tube having a plurality of anodes, a symmetrical output circuit connected between said anodes, a plurality of control electrodes, a cathode, an input circuit connected between one of said control electrodes and said cathode, and a screen electrode interposed between said anodes and said cathode. 90
- 20 8. Means for demodulating electrical oscillations including a cathode ray electron discharge device having a plurality of anodes, a plurality of control electrodes and a cathode including a symmetrical circuit connecting said anodes to said cathode, means for tuning said circuit, an input circuit connected between one of said control electrodes and said cathode, means for tuning said circuit, means for maintaining each of said control electrodes at a different direct current potential with respect to said cathode, a screen electrode between said anodes and said cathode, and means for applying a potential to said screen electrode. 95
- 30 9. Means for demodulating signal modulated currents including a cathode ray electron discharge device having a plurality of anodes, a plurality of control electrodes, an emission element substantially equidistant from each of said anodes, and a screening electrode interposed between said anodes and said emission element, a symmetrical circuit connecting said anodes to said cathodes, means for tuning said circuit, means for applying direct current potential to said anodes, means for applying a different direct current potential to said screening electrode, an input circuit connecting one of said control electrodes to said emission element, and means including an impedance in said input circuit for applying different direct current potentials to each of said control electrodes. 100
- 40 10. A thermionic demodulating device comprising an envelope including a plurality of anodes, a plurality of control electrodes, an emission element spaced equidistant from each anode, means for applying direct current potential to each anode, means for applying signals to said demodulation device including, an input circuit including a tuned inductance connected between 105
- 50 55 60 65 70 75 80 85 90 95 100 105 110 115 120 125 130 135 140 145 150
- one of said control electrodes and said emission element, means for applying a different direct current potential between each control electrode and said emission element, means for causing signal modulations in said input circuit to produce similar potential changes on the anodes of said demodulator including an impedance connected between one of said control electrodes and said emission element, said impedance being traversed by direct current components derived from rectified signal current in the input circuit, and means for preventing reactions between said anodes and said emission element including a static shield interposed therebetween. 80
11. Means for demodulating signal modulated high frequency current including a thermionic tube comprising a plurality of anodes, a plurality of control electrodes symmetrically arranged with respect to said anodes, a cathode equidistant from each anode, a screening grid located between said control electrodes and said anodes, a symmetrical circuit including a tuning condenser connected between said anodes, common means for applying a similar direct current potential to each of said anodes, means for impressing signal modulated oscillations between one of said control electrodes and said cathode including an inductance and a variable condenser, and means for applying a different direct current potential between each of said control electrodes and said cathode, and between said screening grid and said cathode. 90
12. A thermionic demodulator including a discharge device having a plurality of anodes, a plurality of control electrodes, and a cathode, means for connecting said electrodes for grid rectification of the signal including, means for applying the same direct current potential between each anode and said cathode, a tunable repeater circuit symmetrically connected between said anodes, means for impressing signal oscillations between one of said control electrodes and said cathode, means for applying different direct current potentials to said control electrodes and said cathode including, an impedance connected between one of said control electrodes and said cathode, and a screen electrode interposed between said control electrodes and said anodes. 110
13. A means of demodulating signals by a system including, a cathode ray tube having a cathode, a pair of control electrodes, a pair of anodes, and a screen electrode between said control electrodes and said anodes, which comprises energizing one of the control electrodes of said tube at the frequency of the incoming signals, maintaining the control electrodes of said tube at different direct current potentials, feeding the resultant energy from the anodes of said tubes in opposition, and maintaining said screen electrode at a positive potential with respect to said cathode. 120
